(57) **CLAIM**

The ornamental design for a large all terrain utility cart, as shown and described.

DESCRIPTION

FIG. 1 is a left side elevation view of the large all terrain utility cart showing our new design;
FIG. 2 is a left elevation view thereof;
FIG. 3 is a rear elevation view thereof;
FIG. 4 is a front elevation view thereof;
FIG. 5 is a top plan view thereof; and,
FIG. 6 is a bottom plan view thereof.

The dashed lines in the drawings are to show portions of the large all terrain utility cart only and form no part of the claimed design.
